[57] CLAIM

The ornamental design for a fluid regulator or the like, substantially as shown and described.

DESCRIPTION

FIG. 1 is a right side elevational view of a fluid regulator or the like showing our new design, the left side being a mirror image of the right side shown;
 FIG. 2 is a front elevational view thereof;
 FIG. 3 is a top plan view thereof;
 FIG. 4 is a bottom plan view thereof; and
 FIG. 5 is a rear elevational view thereof.
